J. K. Bryant
Attorney

UNITED STATES PATENT OFFICE.

STANLISOUS KOSIENSKI, OF VERNON, NEW YORK.

STAPLE.

Application filed December 19, 1922. Serial No. 607,788.

To all whom it may concern:

Be it known that I, STANLISOUS KOSIENSKI, a citizen of the United States of America, residing at Vernon, in the county of Oneida and State of New York, have invented certain new and useful Improvements in Staples, of which the following is a specification.

The present invention relates to improvements in staples.

A primary object of the invention is to provide an inexpensive, simple in construction and efficient staple.

A further object of the invention is to provide a staple adapted for the purpose of securely attaching wire to a fence post or the like.

A still further object of the invention is to provide a staple constructed for the combined purpose of holding and stretching a wire when driven into a fence post, or the like.

With these objects in view and others which will appear as the nature of the invention is better understood, in the drawing wherein like reference characters denote corresponding parts throughout the several views,

Figure 1 is a cross sectional view of a staple and post with the staple partly driven into the post,

Figure 2 is a view partly in section and partly in side elevation of the staple in its operative position,

Figure 3 is a plan view of a section of fencing showing a portion of the wire attached thereto, and

Figure 4 shows side elevational views of the staple.

The staple consists of a shank or body portion 10 having depending prongs 11 extending therefrom. These prongs 11 have wedge-shaped outer ends or points 12 which are adapted to be easily driven into wood without splitting it. The inner edge of the shank or body portion 11 is provided with slots or grooves 13 which form the ridges or teeth 14 therebetween. These ridges or teeth securely hold the wire when the staple is driven into the wood. Formed on opposite sides of the shank or body portion 10 are two laterally extending shoulders or flanges 15. These flanges diverge downwardly from the head 22 of the shank or

body portion 10 and have at their lower outer edges depending teeth or projections 16 longitudinally disposed in relation to said flanges 15, and are adapted for biting into the wire as shown in Fig. 2.

Referring more in detail to the manner of operation the staple is placed over the wire 17 and driven into the post 18, as shown in Fig. 1, until the ridges or teeth 14 engage the wire. Further driving of the staple will force the wire into the post, as shown at 19 in Fig. 2, while the teeth or projection 16 will bite into the wire for further aiding in securely holding the same. It will be seen that the wire thus driven into the post is safe from being pulled or loosened from its fastening.

It is desirable that the wire be tightly stretched when secured to the posts, but it is oftentimes too rigid to be stretched manually. The staple as herein described will aid in stretching the wire when driven into the post. In Fig. 3 there is illustrated a section of a fence embodying the invention wherein the portion of the wire designated by the numeral 20 has been drawn taut having been stretched upon two posts 18 by the employment of the present staple, while portion 21 is loose preparatory to being secured by the staple to the following post.

While it is herein described a preferred embodiment of the invention, it is nevertheless understood that minor changes may be made without departing from the spirit and scope of the invention as claimed.

What is claimed as new is:—

1. In a staple of the class described, a shank, a plurality of prongs extending from the inner end of said shank, shoulders extending laterally from said shank, and depending projections carried by said shoulders.

2. In a staple of the class described, a shank, prongs extending from the inner end of said shank and terminating in wedge-shaped points, depending projections formed in the inner edge of the shank in the space between said prongs, shoulders laterally extending from the outer end of said shank and being rigid therewith, and longitudinal projections carried by said shoulders.

In testimony whereof I affix my signature.
STANLISOUS KOSIENSKI.
